UNITED STATES PATENT OFFICE.

OLIVER W. STEELE, OF DALLAS, TEXAS.

METER-BOX COVER.

Application filed September 22, 1922. Serial No. 589,950.

To all whom it may concern:

Be it known that I, OLIVER W. STEELE, a citizen of the United States, residing at Dallas, in the county of Dallas and State of Texas, have invented certain new and useful Improvements in Meter Box Covers, of which the following is a specification, reference being had therein to the accompanying drawing.

10 This invention relates to improvements in meter box covers and pertains to a cover that when locked in position requires a key for unlocking it.

15 It is well known that meter boxes are sunk in the ground and a removable cover is necessary to permit access to the box for the purpose of taking the reading, and for repair and replacement of the meter.

20 The primary object of the present invention is to provide a removable cover with a lock which is operated by a key adapted to be passed through a keyhole in the cover and release the lock.

25 Another object of my present invention is to provide the under side of the cover of the box with an approximately U-shaped locking lever that is intermediately pivoted, one arm of the locking lever adapted to engage the under side of the ring of the box, and the 30 other arm adapted to be actuated by a key for unlocking its opposite end.

35 Other objects of the invention will appear from the following description and disclosure of the invention.

Fig. 1 is a top plan view of the meter box cover which embodies my invention.

Fig. 2 is a central cross sectional view taken through the lock.

Fig. 3 is an inverted plan view showing the lock and the key shown in dotted lines.

Fig. 4 is a side elevation of that part of the cover carrying the lock showing it in locked position.

Fig. 5 is a detached perspective view of the key.

Referring now to the drawings:

1 indicates the top of the meter box (not shown) which in the form here shown is round in plan view. It will be understood that the top may be any desired shape without changing my improved lock. The ring 1 has a circular opening 2 which will receive a round cover 3. This cover when in position rests upon an L-shaped supporting member 4 of the ring 1. The edge of the cover is provided with an L-shaped outward-

ly projecting member 5 adapted to interlock under the supporting ledge 4.

The opposite edge of the cover 3 is provided with my improved lock. This lock 60 comprises a bell crank or U-shaped member having an arm 6 and an arm 7. At the junction of the two arms 6 and 7 I provide a pivotal bearing 8 which is pivoted upon a stud which downwardly projects from the 65 under side of the cover 3. The stud 9 projects considerably below the bearing 8 and a counter-pin 10 passes through the stud. The end of the counter-pin is bent as shown at 11 and receives one end 12 of a spring 13. 70 This spring 13 is wound around the stud and its opposite end 14 engages with the pivotal bearing 8.

A key opening 15 is made in the cover 3, and this opening at its under side is provided with a projection 16, which increases in depth at 17 around the pivotal point of the key 18.

Attention is directed to the fact that the arm 7 has an inner curved surface 19 with which a projection 20 of the key engages to force the arm 7 inward when the key is turned. By means of the spring 13 the arm 7 of the locking member is normally held in the position shown in Fig. 3, that is, in contact with the raised portion 17 of the key-hole 15. This position of the locking member throws its lug 21 outwardly under the supporting ledge 4 of the ring 1 and locks the cover in position. When it is desired to unlock the cover the key is inserted far enough to have its part 20 clear the thickened portion 17 when it is drawn outward and then turned which will throw the arms 6 and 7 inward and carry the locking 90 lug 21 out of engagement with the supporting ledge 4.

It will be noted that the distance between the part 20 of the key and the lug 21 is sufficient to provide for the inward movement of the key to pass the raised part 16 of the key-hole. When the key is pulled outward the part 20 is brought in position for working on the curved portion 19 of the arm 7 of the bell crank lever. The key-hole 15 is made angular in shape so that it takes that shape key to enter the hole and the key must have the part 20 and the cut out part 21 in order to perform its function as above stated.

For the purpose of giving strength to the part 6 which carries the lug 21 I provide the

under side of the cover with an L-shaped lug 22 with which the projecting end 23 of the member 6 engages when the lock is in the locking position. The L-shaped member 22 extends toward the lever 6 and at right angles to the supporting ledge 4.

From the foregoing description it will be understood that when putting the cover in position the member 5 is inserted under the supporting ledge 4 and then by turning the key the lug 21 is retracted allowing the cover to rest on the ledge and when the key is removed the lug engages the under side of the ledge 4. As stated when the parts are in their locked positions the member 22 takes the strain if it should be attempted to remove the cover without the key.

I desire it to be understood that my invention is not limited to the precise constructions herein shown and described so long as the changes or modifications are within the scope of the appended claims.

What I desire to secure and protect by Letters Patent is:

1. A lock for a cover comprising a bell crank lever pivoted at the junction of its arms to the under side of the cover, the outer arm adapted to project beyond the cover, a lug carried by the cover engaging the outer arm and a key-hole located between the arms whereby it may be thrown to unlocked position by a key.

2. A lock for a cover comprising a bell crank lever pivoted at the junction of its arms to the under side of the cover, the outer arm having an intermediate lateral projection adapted to project beyond the cover, and a keyhole located between the said arms to receive a key to act on the inner side of the inner arm for withdrawing the said lug within the periphery of the cover.

3. A lock for a cover comprising a bell crank lever pivoted at the junction of its arms to the under side of the cover, the cover provided with a depending lug located to lap over the end of the outer arm, said outer arm constructed to extend beyond the cover for the purpose described, and a keyhole located between the said arms to permit the insertion of the key to act on the inner side of the inner arm for withdrawing the outer arm for releasing the cover.

4. A lock for a cover comprising a bell crank lever, pivoted at the junction of the arms to the under side of the cover, the cover having a depending L-shaped lug adapted to overlap the extremity of the outer arm, the outer arm having a projection extending laterally outward from the said arm for the purpose described, a keyhole located between the said arms adapted to receive a key to engage the inner side of the inner arm for withdrawing the said lug.

5. A lock for a cover comprising a bell-crank lever, pivoted at the junction of its arms to the under side of the cover, the outer arm constructed to extend beyond the said cover, the cover having a keyhole located between the said arms, the keyhole provided with a depending flange in the line of travel of the inner arm, and a spring for holding the inner arm in engagement with the said flange. 75

6. A lock for a cover comprising a cover, a bell crank lever pivoted at the junction of its arms to the under side of the cover, the outer arm of the lever having a lug adapted to project beyond the cover and a keyhole located between the arms of the lever. 80

7. A cover lock comprising a cover, a bell crank lever, a keyhole located between the arms of the lever, one arm of the lever adapted to project outwardly to lock the cover in place, and the keyhole opening provided with a projecting wall to form a stop for the lever. 85

8. A cover lock comprising a cover, a bell crank lever, a keyhole located between the arms of the lever, the outer arm of the lever adapted to project outwardly to lock the cover in place, a spring engaging the lever to hold it in its locked position, a keyhole opening provided with a projecting, surrounding wall adapted to engage the inner arm of the lever, and means to move the lever against the tension of the spring, for the purpose described. 90

9. A lock for a cover comprising a cover, a bell crank lever pivoted to the under side of the cover, an annular shaped keyhole located between the arms of the lever, the keyhole opening provided with a projecting, surrounding wall, the surrounding wall at one end of the angular keyhole opening higher than at the other end, whereby a key of a particular shape is required to operate the lever, for the purpose described. 105

10. A lock for a cover comprising a bell crank lever pivoted to the under side of the cover, the outer arm of the lever adapted to project outwardly to lock the cover in place, a coil spring having one end attached to the lever and its opposite end to the lever pivot to normally hold the lever in an outwardly extended position, the parts operating as described. 115

11. A lock for a cover comprising a bell crank lever pivotally mounted upon the under side of the cover, the outer arm of the crank adapted to project outwardly, a lug carried by the cover engaging the arm, and means to move the lever, for the purpose described. 120

In testimony whereof I hereunto affix my signature.

OLIVER W. STEELE.
